(Cl. D85—2)

To all whom it may concern:

Be it known that we, James Murray Beveridge and Clifton J. Cowan, citizens of the United States of America, residents, respectively, of Bronxville, in the county of Westchester and State of New York, and of East Orange, in the county of Essex and State of New Jersey, have invented a new, original, and ornamental Design for a Cigarette Case, of which the following is a specification, reference being had to the accompanying drawing, forming a part thereof.

In the drawing:

Figure 1 is a perspective view of an open cigarette case, showing our new design; and

Figures 2, 3 and 4 are typical sectional views through the cigarette case taken on the lines 2—2, 3—3 and 4—4, respectively, of Figure 1.

The dominant features of my design reside in the appearance of the interior of the cigarette case shown.

We claim:

The ornamental design for a cigarette case, as shown and described.
